United States Patent

Des. 235,246
Patented June 3, 1975

235,246

PACKAGING CONTAINER

David E. Evans, Jr., Bexley, and James W. Murray, Columbus, Ohio, assignors to The Columbus Dental Manufacturing Company, Columbus, Ohio

Filed Mar. 21, 1973, Ser. No. 343,449

Term of patent 14 years

Int. Cl. D9—03

U.S. Cl. D9—222

FIG. 1 is a perspective view of a packaging container showing our new design;

FIG. 2 is a side elevational view;

FIG. 3 is a top plan view;

FIG. 4 is a bottom plan view; and

FIG. 5 is an enlarged, medial vertical sectional view taken along a plane indicated by the line 5—5 of FIG. 1.

We claim:

The ornamental design for a packaging container, substantially as shown.
